9 Claims. (Cl. 226—5)

1

This invention concerns improvements in or relating to collecting mechanism for cigarettes and other rod shaped articles and used for collecting cigarettes produced by a cigarette making machine, in receptacles.

A continuous rod cigarette making machine comprises a long bed on which the rod is made and cut into separate cigarettes which are delivered on to a conveyor band (the catcher band) which is supported on a frame or bracket projecting at right angles to said bed. In order to collect the cigarettes from the band it is common to provide a track or path along which receptacles can be moved beneath the band so that cigarettes can roll from the band down suitable guides into a receptacle which is moved, as by a conveyor, so that while being filled it travels along parallel to the band. A receptacle is as wide as the length of a cigarette and its length and height depend on the capacity desired. In filling, the receptacle moves lengthwise. Thus, collecting mechanism of the kind referred to, as hitherto constructed, requires a good deal of floor space for its accommodation and although part of it may be disposed beneath the catcher frame it is desirable that as far as possible the collecting mechanism should be confined within the area normally occupied by the cigarette machine.

An object of the invention is to provide an improved collecting mechanism which occupies very little floor space but is as efficient and accessible and of a capacity as great as existing collecting mechanism.

According to the invention there is provided cigarette collecting mechanism of the kind referred to comprising support carriages for receptacles, conveyor means for moving said support carriages individually along two runs in opposite directions, one portion of one run being beneath a filling position and a switching device for switching a carriage moving on one of said runs from said run to the other run, by a reversing movement, so that the leading end of a carriage on one run becomes the trailing end on the other run. The support carriages may be moved in a closed path and a switching device may be provided at each end of said runs for switching the carriages from one run to the other run.

The conveyor means may be provided with coupling elements at intervals adapted to couple

2

and uncouple respectively said carriages and the conveyor means, and means may be provided for automatically coupling and uncoupling the carriages and conveyor means in such manner that carriages will be so spaced that receptacles carried by them are in abutting relationship whilst the abutting parts are passing the filling station and at other times are spaced apart to enable the carriages to be switched.

10 Further according to the invention there is provided cigarette collecting mechanism of the kind referred to comprising an endless conveyor moving in a substantially horizontal path and having two straight runs, one passing beneath a filling position, abutments at intervals on said conveyor adapted to engage and disengage tray-supporting carriages movable by said abutments with said conveyor on an associated track, and a switching device at each end of said straight 15 runs for reversing a carriage moving on one of said runs and switching it on to the other said run.

20 The conveyor may be constructed as a chain conveyor with parallel runs and pass around sprocket wheels rotatable on vertical spindles at each end of the conveyor path. The abutments may be pegs or the like equally spaced along the length of the chain and projecting vertically upwards therefrom.

25 The track may comprise a support plate having a surrounding rim and other guides whereby carriages are supported and controlled or steered. The carriages may be of substantially rectangular shape in plan and have small feet or abutments 30 of circular cross section to engage the plate and rim of the track. Carriages may be coupled to the conveyor for movement therewith by movable members attached to the carriages and adapted to engage and disengage the conveyor abutments. 35 A member may be held in engaging position by a spring and disengaged by contact with a cam or abutment disposed at an appropriate position on the track for a purpose which will be understood from the specific description given later.

40 A switching device may comprise an abutment or fulcrum at each end of the track against which a part of a carriage may abut and so located 45 relatively to the point of attachment between carriage and conveyor that continued conveyor

movement swings or slews a carriage about said fulcrum.

Means may be provided for stopping the conveyors should the supply of cigarettes fail.

One way of carrying the invention into effect will be described with reference to the accompanying drawings in which—

Figure 1 is a front elevation of cigarette collecting mechanism constructed according to the invention, with a few parts in section.

Figure 2 is a plan of Figure 1 certain driving devices and cigarette feeding arrangements being omitted.

Figure 3 is an end elevation of Figure 1 looking in the direction of the arrow A, a few parts being in section.

Figure 4 is a plan of part of Figure 1 showing the driving devices omitted from Figure 2.

Referring to the drawings the mechanism comprises an endless chain conveyor 1 having two parallel straight runs, see Figure 2, and passing around sprocket wheels 2 and 3 at the ends of said runs. The sprocket wheels are fixed to vertical spindles 4 and 5 journalled in suitable bearing brackets 6 and 7, Figure 1, which are fixed to a baseplate 8 which may rest on the floor or, as shown, may be adjustably supported from the floor by screw jacks 9. The conveyor is driven by a ratchet wheel 10, Figure 3, fixed to the spindle 5 of the sprocket wheel 3 and rotated by an oscillating double pawl 11, see also Figure 4, (not shown) being also provided. The driving pawl 11 is pivoted on an arm 13 of a double-armed lever, the pivot 15 of the lever being fixed to the baseplate 8. The other arm 14 of the double-armed lever is pivoted to one end of a connecting rod 16 which is pivoted at its other end to cam lever 17. The lever 17 is pivoted to the baseplate 8 and has a roller 18 at its end which engages a cam 19. The cam is fixed on a shaft 21 supported in bearings on the baseplate 8 and having a sprocket wheel 22 fixed on it, which is driven by a chain (not shown) from the cigarette machine to which the collecting mechanism is attached. A spring 20 returns the connecting rod 16. Thus as the cigarette machine runs the conveyor is intermittently driven. This is a convenient arrangement but an independent motor might be used or continuous drive by gearing from the shaft 21 or the motor might be employed.

Above the conveyor there is fixed a conveyor track, generally indicated by the reference 23, which is supported by brackets 24 from the baseplate 8 and will now be described. At either side of each run of the conveyor, see Figures 2 and 3, and equally spaced from said run is an angle iron or like member 25 and 26 respectively, one limb of a member being fixed to the aforesaid bracket 24 and the other projecting upwards, the arrangement being such that the two angles form a channel shaped guide along each conveyor run. The inner angle members 26 each terminate at a position some distance before the neighbouring sprocket wheel is reached, see Figure 2, but a continuation of the horizontal surface of said members is provided, by plates 27 and 28 fixed to the top of the neighbouring support brackets 24 extending lengthwise and laterally as shown. The outer angle members 25 are longer and each extends some inches beyond the sprocket wheel centres and joins platforms, 30 and 31 respectively whose surfaces are at the same level as that of those limbs of the angles 25 and 26 which are fixed to the support brack-

ets. Each platform has a rim 32 and 33 respectively whose height is the same as that of the vertical limbs of the angle members and thus these rims form a continuation of the outer angle member limbs 25. The platform rims are shaped as shown in Figure 2. The purpose of the plates 27 and 28 and the platforms 30 and 31 and rims 32 and 33 is to assist in switching and reversing carriages which are moved over the track by the conveyor. To the platforms there are fixed switching members 34 and 35 respectively so shaped (e. g. concave) that a foot 37 of a carriage described below will pivot on it, the switching member acting as a fulcrum.

The carriages generally indicated by the reference 36 which are moved over the conveyor track are of substantially rectangular oblong shape in plan, at least as regards the base thereof, and on a straight run the oblong extends lengthwise along the conveyor track. Each carriage has eight small circular studs or feet 37 having a convex base, on which the carriage rides on the track. At the centre of the carriage base is an apertured member 38 and at equal spaces along the conveyor chain are disposed rounded pegs 39 adapted to enter the aperture in the carriage member 38 and drag the carriage over the track. On the straight run which is the lower in Figure 2 the carriage moves in a straight line in the direction of the arrow, Figure 2, being guided by its feet 37 and the angle members 25 and 26 but as it approaches the end of said straight run the outer leading foot is guided by the platform rim at the right hand end, Figure 2, until it encounters the switching member 35. This is so disposed relatively to the neighbouring sprocket wheel 3 that the chain moves round the wheel and the centre of the carriage conforms to the movement but as the leading outer corner of the carriage is arrested the carriage slews round on this corner, the switching member acting as a fulcrum and on further movement the former rear end of the carriage advances on to the other straight run of the conveyor track and the carriage proceeds along this run with its former rear end leading, see upper arrow in Figure 2, and the arrested corner is drawn away from the switching member. The filling run is in the direction of the lower arrow Figure 2. As during the switching movement the rear of a carriage swings towards the line joining the sprocket wheel centres the inner angle guides 26 terminate at the positions formerly described to allow the carriage to move over on the aforesaid continuation of the horizontal surface formed by the plate 28. The leading end of the carriage (just before reversal) is well supported by the platform 31 and the rear inner stud 37 slides over the plate 28 from one guide 26 to the other and so transition from one run to the other is smooth and easy. At the other end of the track the movement is repeated. The upper side of a carriage forms a platform on which are supported two trays or receptacles 40 (for a double row catcher band) into which cigarettes are fed as will now be explained.

One straight run of the conveyor lies vertically below the centre line of the catcher band of the cigarette machine. Feeding devices such for example as hose described in British patent specification No. 549,877 which are here indicated by the reference 41 are provided with suitable means 42—43 for guiding the cigarettes into the trays so that as the latter pass beneath the end of the band they become filled.

The part 42 is merely a steel plate but the part 43 is a flexible strip of fabric or the like on which metal slots (e. g. brass) are fixed. This provides a very satisfactory guide as the part 43 straightens the cigarettes where necessary so that they lie properly in the tray.

As the output of the cigarette machine is continuous it is necessary that trays shall be in abutting relationship as they pass the filling position, or the gaps therebetween suitably bridged, or otherwise cigarettes would be spilled on to the conveyor. The trays used in the present case are such that in the drawings bridging is shown and will be described below.

The apertured member 38 above referred to forms the free end of a lever 44 pivoted at 45 on the carriage and is urged into operative engagement with a conveyor peg 39 by a spring 46. When the forward end of a carriage has passed beneath the filling position by, for example, about one-third of the length of the carriage the lever 44 is tripped by a cam 47 at the side of the conveyor track and the carriage stays still for a short time, the filling operation still of course continuing. In Figure 1 the left-hand carriage has just stopped. The carriage behind the stationary one shortly afterwards comes into contact with it and pushes it along beneath the filling position until such time as the second carriage is in the position where the first was when its lever was tripped. Then the lever 44 of the second carriage is tripped and it stays still and the first carriage which is merely pushed by the second also stays still. But while the first carriage has been pushed by the second, the lever of the first carriage has passed clear of the cam and moved down under its spring so that when the second carriage stops and the first carriage naturally stops again, the apertured member 38 is ready for re-engagement with the next passing peg of the conveyor. This peg raises the lever slightly on meeting it, see lever at right hand of Figure 2 near sprocket 3, so that the peg can enter the aperture whereafter the first carriage is again moved along by the conveyor instead of being pushed by the second carriage. In this way carriages passing the filling position can have their trays abutting if they are of suitable shape and the filling of one tray starts as that of the preceding one finishes.

The bridging of the gaps between the ends of the trays passing the filling position is effected by twin levers 52 pivoted at 53 at that end of each carriage which is leading during a filling run, that is, along the lower run in Figure 2. The levers which are shaped as shown in Figure 1 so that they enter the spaces between the forks of two neighbouring trays are kept in their proper position during transit past the filling station by a cam track 54 in which run rollers 55 attached to levers 56 depending from the pivot pin 53 see Figure 1. When a full tray is lifted off the carriage the levers 52 belonging to the next carriage will tilt by gravity to the position shown at the right hand end of Figure 1 and clear the tray on said carriage.

As a carriage moves on the idle run, which is at the back in Figure 1, and along which the carriages move leftwards as viewed in that figure the levers 52 will continue to hang back, that is in the position shown at the right hand of Figure 2. It is necessary to put the levers more within the confines of the carriage or as the carriage switches over to the front or filling run the levers will strike the tray and carriage which is on

the front run. This movement is effected by a hook shaped pawl 64 which engages said roller 55 and causes the levers 52 to swing on the pivot 53 anti-clockwise and in toward the adjacent end of the carriage until they are tilted in the reverse direction, see left-hand carriage in Figure 2. Continued movement of the carriage causes the roller 55 to move out of the curved hook, but as the levers 52 are comparatively massive and balanced about the pivot they stay in the back tilted position (that is, as on the left-hand carriage in Figure 2) as the carriage switches on to the front or filling run whereupon the roller 55 enters the flared end of the track and the levers are brought to their proper position. Pins 65 control the extent of the pawl movements.

If for any reason the supply of cigarettes should fail a detecting device cooperating with the cigarette feed is arranged to stop the conveyor movement. The device comprises a pivoted feeler 57 which presses on a double armed lever pivoted at 58 and thus causes a rod 59 to move. The lower end of the rod is coupled at 60, Figure 3, to a pawl 61 pivoted at 62, Figure 4. When the pawl drops low enough (i. e. no cigarettes) it takes over the edge of a bar 63 which extends from the arm 14 (see Figure 4) and thus prevents the pawl 61 from making a working stroke under the action of the spring 20. The large spring 120 is merely a safety device. It holds two parts which form the connecting rod 16 together but will yield if a jam occurs.

The trays used on the device may be of any shape as the mechanism can be made to suit any suitable receptacle.

The upper part of a carriage is provided with devices such as guard rails or walls 48 suitably shaped to receive and locate the trays and beneath the trays are arranged shields and guides 49 to direct any tobacco or short ends falling from the trays to a suitable collecting position. Pivoted stop plates 66 cause the tobacco to collect on the guides and when a carriage is on the idle run (right hand of Figure 3) the stop plate can be lifted so that the tobacco slides into a box or the like.

In the specific example given where fairly small trays are used, it happens that their capacity is moderate (about 1500 cigarettes), it is not necessary to vary the conveyor speed at the time of transition of two abutting or neighbouring receptacles, respectively into and out of the filling position. Where large, deep trays are used a variable speed gear may be used for driving the conveyor on the lines of that described in British patent specification No. 549,878. As it is necessary to support the chain of the conveyor to prevent sag, a guide rail 50, Figure 3, conforming to its path is fixed beneath the chain which is supported on the rail by pegs or feet 51 projecting from the chain and riding on the rail. Conveniently these pegs are integral with the carriage engaging pegs above described.

In operating the device the conveyor is started as soon as cigarettes are ready and the carriages move as above described with trays abutting or close and bridged where they pass the filling position and with the carriages spaced apart on the other run of the conveyor which is more remote from the cigarette machine. The operator removes filled trays which are then usually taken to an inspection table where they are supported on a turntable to enable the ends to be inspected. Empty trays are put on carriages from which full ones have been removed and the proc-

ess is continuous subject to the controls described which stop the conveyor when the supply fails or when the cigarette machine stops.

It will be seen that by this invention the conveyor and track can be smaller than in cases where a tray is carried along straight runs of a track and round the ends thereof in the conventional manner and the whole mechanism is much more compact than existing collecting mechanism.

We claim:

1. Cigarette collecting mechanism of the kind referred to comprising support carriages for receptacles, an endless conveyor moving in a substantially horizontal path and having two straight runs, one passing beneath a filling station, a guide track for carriages adjacent said conveyor, coupling means connecting each carriage to said conveyor whereby the carriage is drawn along said track, and a switch device for switching a carriage moving in one of said runs to the other of said runs by a reversing movement, so that the leading end of a carriage on one run becomes the trailing end on the other run, said switch device comprising an abutment associated with the track and positioned for engagement by the carriage to arrest the leading end of the carriage, said abutment being so located relatively to the point of connection between carriage and conveyor that continued conveyor movement swings or slews the carriage about said fulcrum onto the other run.

2. Cigarette collecting mechanism as claimed in claim 1 comprising filler members movable with the carriages and adapted to fill gaps between the adjacent ends of neighbouring carriages so that a smooth continuous cigarette receiving surface is provided between two neighbouring carriages passing the filling position.

3. Cigarette collecting mechanism as claimed in claim 2 wherein a filler member comprises a lever pivoted on a carriage and having a flat top which extends from the flat upper surface of said carriage to the similar neighbouring surface of a preceding carriage and a cam follower attached to said lever and running in a cam track thereby holding said member in the operative position while said carriages are passing the filling position.

4. Cigarette collecting mechanism as claimed in claim 3 wherein said lever is arranged to swing on its pivot to move its flat top away from the carriage to which it is attached when the preceding carriage is removed from the mechanism, comprising means for causing said lever to swing back to its former position before the carriage is switched on to the run passing the filling position for the purpose described.

5. Cigarette collecting mechanism as claimed in claim 1, comprising filler members movable with the carriages and adapted to fill gaps between the adjacent ends of neighboring receptacles so that a smooth continuous cigarette receiving surface is provided between two neighboring receptacles passing the filling position.

6. Cigarette collecting mechanism of the kind referred to comprising support carriages for receptacles, an endless conveyor moving in a substantially horizontal path and having two straight runs, one passing beneath a filling station, a guide track for carriages adjacent said conveyor, coupling means connecting the central portion of each carriage to said conveyor whereby the carriage is drawn along said track, and a switch device for switching a carriage moving in one

of said runs to the other of said runs by a reversing movement, so that the leading end of a carriage on one run becomes the trailing end on the other run, said switch device comprising an abutment associated with the track and positioned for engagement by the leading end of carriage to retard the forward movement of that end of the carriage, whereby continued conveyor movement swings or slews the carriage about said fulcrum onto the other run.

7. Cigarette collecting mechanism of the kind referred to comprising support carriages for receptacles, an endless conveyor moving in a substantially horizontal path and having two straight runs, one passing beneath a filling station, a guide track for carriages adjacent said conveyor, coupling means connecting the central portion of each carriage to said conveyor whereby the carriage is drawn along said track, said coupling means comprising a plurality of pegs on said conveyor, and an apertured member on each of said carriages for receiving a conveyor peg, and a switch device for switching a carriage moving in one of said runs to the other of said runs by a reversing movement, so that the leading end of a carriage on one run becomes the trailing end on the other run, said switch device comprising an abutment associated with the track and positioned for engagement by the leading end of carriage to retard the forward movement of that end of the carriage, whereby continued conveyor movement swings or slews the carriage about said fulcrum onto the other run.

8. Cigarette collecting mechanism of the kind referred to comprising support carriages for receptacles, an endless conveyor moving in a substantially horizontal path and having two straight runs, one passing beneath a filling station, a guide track for carriages adjacent said conveyor, coupling means pivotally connecting each carriage at a point substantially midway of its length to said conveyor, whereby the carriage is drawn along said track, and a switch device adjacent the end of each run for switching a carriage moving in one of said runs to the other of said runs by a reversing movement, so that the leading end of a carriage on one run becomes the trailing end on the other run, each switch device comprising an abutment associated with the track and positioned for engagement by the carriage to arrest the leading end of the carriage, said abutment being so located relatively to the point of connection between carriage and conveyor that continued conveyor movement swings or slews the carriage about said fulcrum onto the other run.

9. Cigarette collecting mechanism of the kind referred to comprising support carriages for receptacles, an endless conveyor moving in a substantially horizontal path and having two straight runs, one passing beneath a filling station, a guide track for carriages adjacent said conveyor, coupling means pivotally connecting each carriage at a point substantially midway of its length to said conveyor, whereby the carriage is drawn along said track, and a switch device adjacent the end of each run for switching a carriage moving in one of said runs to the other of said runs by a reversing movement, so that the leading end of a carriage on one run becomes the trailing end on the other run, each switch device comprising an abutment associated with the track and positioned for engagement by the carriage to arrest the leading end of the carriage, said

abutment being so located relatively to the point of connection between carriage and conveyor that continued conveyor movement swings or slews the carriage about said fulcrum onto the other run, and stationary means adjacent said filling station for engaging and releasing said coupling means as each carriage moves into position beneath said filling station, whereby each carriage remains in filling position until moved beyond such position by the succeeding carriage.
